CLAIM

The ornamental design for a clip for organizing notes and photographs, as shown and described.

DESCRIPTION

FIG. 1 is a perspective view of a clip for organizing notes and photographs.

FIG. 2 is a bottom view of the clip of FIG. 1.

FIG. 3 is a top view of the clip of FIG. 1.

FIG. 4 is a side view of the clip of FIG. 1; and,

FIG. 5 is another side view of the clip of FIG. 1.

The surface shading illustrated in the drawings is provided merely to highlight the contour of design; it is not intended to be illustrative of texture or gloss.
